UNITED STATES PATENT OFFICE.

WALDEMAR PETERSEN, OF DARMSTADT, GERMANY, AND WILHELM HESS, OF BASEL, SWITZERLAND, ASSIGNORS TO THE FIRM OF EMIL HAEFELY & CIE. A. G., OF BASEL, SWITZERLAND.

HIGH-TENSION TRANSFORMER.

Application filed January 26, 1922. Serial No. 532,027.

To all whom it may concern:

Be it known that we, WALDEMAR PETERSEN, a citizen of the Republic of Germany, and resident of Darmstadt, Germany, professor, and WILHELM HESS, a citizen of the Swiss Republic, and resident of Basel, Switzerland, have invented new and useful Improvements Relating to High-Tension Transformers, of which the following is a full, clear, and exact specification.

This invention relates to high tension transformers of the kind in which the coils of the high tension winding are carried upon an insulating hollow sleeve or cylinder which is separated from the low tension winding and the core by an air jacket of ample dimensions, so that stratified or strip like electric discharges only and not brush or spark discharges can take place in the high tension field. In order to utilise the air space as satisfactorily as possible a conducting discharge ring is provided at the high potential end of the high tension winding, this ring being designed to promote uniformity in the strip like discharges. In the case however of a very high tension transformer and more particularly when the transformer has one terminal earthed, the uniformity and regularity of the strip like discharges are liable to considerable disturbances owing to slight deviations from symmetry in the electro-static field as, for example, when the transformer is situated with one side in the vicinity of a wall.

The present invention has for its object to provide arrangements applicable to single or poly-phase transformers of the above general character for more effectively stabilizing the electrostatic field at the portions of the high tension insulation which are not covered by the winding. According to the present invention one or more stabilizing rings are provided in the space surrounding the high tension insulation beyond the winding, the ring or rings being so formed and situated that a stabilization and as uniform a distribution as possible are produced in the electrostatic field.

The stabilizing ring or rings may be of any suitable shape, being for instance of circular or angular cross section.

When several stabilizing rings are employed these may, as regards their potentials, be graduated by a potential determining device, acting either by conduction, by induction, or by capacity, so that the several rings are maintained at potentials corresponding to their distances from the high tension winding.

The invention is illustrated in the accompanying diagrammatic drawings of which—

Figures 1, 2, 3 and 4 are views in side elevation partly sectional of high tension transformers of the type above referred to and embodying various forms of the invention. Figure 5 shows a further modified arrangement.

In the construction shown in Figure 1 the primary or low tension winding *a* of the transformer is arranged on the iron core *b* and is surrounded by air air-jacket *f*, the outer wall of which is constituted by the hollow insulating cylinder *g* which carries the high tension winding *h*. The latter at its high tension end is enclosed by a discharge ring *i* from which proceed slight stratified or strip like discharges along the cylinder *g*.

In order to create on the free upper part of the insulating cylinder *g* situated between the upper extremity of the high tension winding *h* and the iron yoke *b* and also in the surrounding air an electrostatic field which is as uniform as possible, there are arranged in this space several independent stabilizing rings *r*, *r'* insulated and at appropriate distances both from each other and from the high tension end of the winding *h*, the potentials of these rings being adjusted so as to be graduated according to their distances from the winding *h*. In the case of a 150,000 volt transformer two stabilizing rings *r*, *r'*, for instance, may be employed of which the one, *r*, situated adjacent to the winding *h* will be maintained at 100,000 volts, the other, *r'*, being main-

tained at 50,000 volts. This may be effected by providing a conductor s or s^1 which is connected to a tapping in the high tension winding h corresponding to the required potential of the ring. As shown in Figure 5, the rings r , r^1 may also, however, be brought to the desired potentials by means of other electric potential-determining devices such as, for instance, the one r by means of a capacity G , the other r^1 by means of an inductance L , or also an ohmic resistance, if desired.

If it is desired to dispense with potential-determining devices the conductors s , s^1 will be unnecessary, and by giving suitable dimensions to the stabilizing ring or rings, their own electrostatic capacity may be so determined that their potential is adjusted to the desired value.

In direct electrical connection with the iron yoke b as shown in Figure 1 a dished stabilizing ring t is provided, which, extending outwards to a considerable distance and being at the same potential as the core, contributes to the promotion of uniformity of electrostatic field distribution. The ring t may also in certain cases be made use of as a support from which to suspend the rings r , r^1 by suitable insulators or insulating members, as indicated by dotted lines at m (Fig. 1), although the rings may also be supported in other ways, as for example, by arranging that a lower ring shall be carried by a higher one with suitable insulators interposed, thus saving insulating material and necessitating insulation only for the voltage between adjacent rings.

For transformers of lower voltage, one stabilizing ring may be sufficient, while for those of higher voltage more than two such rings may be employed, the voltages of which are correspondingly graduated. Generally speaking, the number of stabilizing rings will be determined by the voltage of the transformer.

In Figure 2 a construction is illustrated in which, for example, only one stabilizing ring t^1 is employed. In this case it is advisable that the stabilizing ring t^1 shall be of a roof-like form or have the form of a roof-like conical sleeve.

Figure 3 represents a single-phase transformer, provided on one high tension limb with three stabilizing rings r , r^1 , r^2 , the upper one, r^2 , of which is connected by a conductor s^2 to a point of suitable potential in the winding h^1 on the other limb. It is of course possible to mount stabilizing rings on both limbs of the core, but this is not always necessary when one end of the transformer winding is earthed.

In applying the invention to three-phase transformers one or more stabilizing rings may, with advantage, be provided for each limb of the core, the dimensions of the rings

being adapted to correspond to the different capacities of the several limbs with regard to each other or to the adjoining space, for instance, the tank of an oil-transformer.

Figure 4 shows an arrangement similar to that of Figure 1, with the exception that the electric potential impressing connections s , s^1 of the stabilizing rings r , r^1 are provided with one or more high ohmic resistances w , w^1 . These provisions have the purpose to bring the phase conditions of the tension of the stabilizing rings to any desired value, and on accidental breaking down to limit the current impulsion in the stabilizing rings and to damp over-tensions on electric oscillations.

What we claim is:—

1. A high tension transformer of the kind described, comprising an iron core with leg and yoke, concentric insulating bodies around the whole length of the leg thereof, low tension and high tension windings around a part of said insulating bodies, an ample free air space between the latter, and a stabilizing ring arranged around the outer insulating body in the space between the high tension end of the high tension winding and the yoke of the core.

2. A high tension transformer of the kind described, comprising an iron core with leg and yoke, concentric insulating bodies around the whole length of the leg thereof, low tension and high tension windings around a part of said insulating bodies, an ample free air space between the latter, stabilizing rings arranged around the outer insulating body in the space between the high tension end of the high tension winding and the yoke of the core, and potential determining devices designed to positively maintain said rings at graduated potentials according to their distances from the high tension winding.

3. A high tension transformer of the kind described, comprising an iron core with leg and yoke, concentric insulating bodies around the whole length of the leg thereof, low tension and high tension windings around a part of said insulating bodies, an ample free air space between the latter, and a cover-like stabilizing ring arranged around the outer insulating body in the space between the high tension end of the high tension winding and the yoke of the core and so shaped as to produce by its relative own electrostatic capacity alone a uniform distribution of the electrostatic field.

4. A high tension transformer of the kind described, comprising an iron core with leg and yoke, concentric insulating bodies around the whole length of the leg thereof, low tension and high tension windings around a part of said insulating bodies, an ample free air space between the latter, a

stabilizing ring arranged around the outer insulating body in the space between the high tension end of the high tension winding and the yoke of the core, and conductive potential determining devices designed to positively maintain said rings at graduated potentials according to their distances from the high tension winding, said devices comprising one or more high ohmic resistances.

In witness whereof we have hereunto signed our names this 7th day of January 1922.
